MAURITS J. SANDIN, OF WILKINSBURG, PENNSYLVANIA, ASSIGNOR TO WESTINGHOUSE ELECTRIC & MANUFACTURING COMPANY, A CORPORATION OF PENNSYLVANIA.

THERMAL CUT-OUT.

Application filed January 23, 1923, Serial No. 614,378. Renewed September 18, 1926.

My invention relates to thermal cutouts and particularly to circuit-interrupting cutouts of the plug type adapted for use in standard socket receptacles.

5 In my copending application for thermal cutouts, Serial No. 614,379, filed January 23, 1923, I have disclosed a cutout device wherein relatively movable terminals are mounted within a plug receptacle and connected by a 10 thermal-responsive refill comprising a contact disc and a heating conductor soldered thereto. When the conductor has attained a predetermined temperature, the solder is fused, thereby releasing the contact member 15 from the heating conductor, the former being rapidly moved away from the latter by a spring. The thermal-responsive refill is of such character that it serves to interrupt the circuit under both overload and short-circuit 20 conditions.

The construction disclosed in the above copending application is designed for operation in circuits carrying a definite range of current and is particularly adapted for use 25 where the current exceeds approximately five amperes. An object of my present invention is to provide a thermal-responsive cutout similar in character to that illustrated in the above-mentioned application but which is designed for carrying heavier currents or for 30 carrying similar currents for a longer period of time.

Another object of my invention is to provide a cutout device wherein the refill is of 35 simple and inexpensive construction and which may readily be replaced within the plug receptacle.

Another object of my invention is to provide a cutout device, having the above characteristics, wherein a heat-absorbing member surrounds the heating conductor of the refill or thermal-responsive element for rendering the heating conductor capable of carrying heavier currents for a conductor of predetermined size and wherein the time characteristics of the thermal-responsive element may be varied by using heat-absorbing members of different proportions.

Another object of my invention is to provide a cutout device wherein the heat-absorbing member is in the form of a tube which fits over the heating conductor of the refill and is adapted to be moved longitudinally

thereof when the members of the refill are released and to move over the released end of 55 the heating conductor for the purpose of cooling and snuffing out the arc incident to the separation of the members of the refill.

Another object of my invention is to provide a cutout device wherein the terminals 60 and plug receptacle are so protected from the heated arc gases that no injury can be done thereto, therefore rendering the device capable of repeated use.

These and other objects, that will be made 65 apparent throughout the further description of my invention, are attained by means of the apparatus hereinafter described, and illustrated in the accompanying drawings, where- 70 in:

Figure 1 is a longitudinal sectional view of a cutout device embodying features of my invention;

Fig. 2 is an end view of the device shown in Fig. 1 with the cover removed;

Fig. 3 is a transverse section through the device taken on the line III—III of Fig. 1;

Fig. 4 is a longitudinal section through a modified form of cutout device, and

Fig. 5 is a longitudinal section through a 80 further modification of the device.

Referring to the drawings, the device includes an insulating casing 6, preferably made of porcelain or insulating compound, having one end closed and provided with 85 bores 7 and 8, the latter being of greater diameter than the former. A tubular terminal 9 is secured to the closed end of the casing 6 by a flange 11 that is spun into engagement with the inner walls of the casing, 90 as indicated in Fig. 1. The tubular terminal is provided with a bore 12 for receiving a refill, to be hereinafter described.

A threaded terminal sleeve 13 is attached to the closed end of the casing exteriorly 95 thereof and is provided with two flexible and yielding terminal members 14 that extend into the bore 8 through openings 15 in the casing. The terminal members 14 are bent inwardly, as indicated in Fig. 1, and are provided with concave contact surfaces 16 for yieldingly and slidably engaging a contact disc 17 that is part of a thermal-responsive element or refill 18 which includes the contact disc 17 and a heating conductor 19 that is 100 preferably made of a nickel alloy or other

relatively high-resistance metal. One end of the heating conductor 19 is inserted through a perforation 21 in the contact disc 17 and is connected thereto by a small portion of solder 22.

The refill 18 is assembled in the device by inserting it through the open end of the casing in such manner that the inner end of the heating conductor 19 is inserted in the bore 12 of the terminal 9. The flanges 23 of the contact disc 17 slidably engage the concave contact surfaces 16 of the terminal members 14 as the refill is being inserted and cause the surfaces to be cleaned as the refill is moved to assembled position. The yielding terminals 14 insure a good conductive contact between the contact discs 17 and the contact surfaces 16. The refill is retained in assembled relation within the casing by a set screw 24 in the terminal 9 which clamps the heating conductor in the bore 12 thereof.

A tubular heat-absorbing member 25 is disposed within the bore 7 concentric to the axis thereof through which the heating conductor 19 extends. The tube is preferably made of aluminum which, when oxidized, prevents conductive connection between the tube and the heating conductor or the associated contact discs 17. However, the tube 25 may be made of porcelain or other insulating heat-absorbing material. The tube 25 is pressed into engagement with the contact disc 17 by a helical spring 26 that is disposed between the end wall of the casing and a movable supporting washer 27 upon which the inner end of the tube 25 is seated. The end of the tube in engagement with the contact disc is countersunk to provide a space 28 surrounding the solder connection. The absence of cooling metal in the vicinity of the solder joint insures that the heating conductor will attain its highest temperature at the point of joinder of the conductor with the contact disc.

When an overload persists for a predetermined time in the circuit in which the thermal-responsive element 18 is connected by means of the terminals 9 and 13, the temperature of the heating conductor at the point of joinder with the contact disc will rise to the fusing temperature of the solder and release the contact discs therefrom. The spring 26 will then instantly force the tube 25 toward the enlarged open end of the casing to the position indicated in dotted lines. The tube 25 is moved over the released end of the heating conductor 19 and instantly cools and snuffs out the arc incident to the separation of the contact disc 17 and the heating conductor 19. In fact, the tube 25 snuffs out the arc before the contact disc has become entirely separated from the terminals 14.

By reason of this construction, the arc is confined to the point of separation of the contact disc and the heating conductor and no

injury to the terminals results. Consequently, the device may be used repeatedly. As a further precaution against heated gases coming into contact with the helical spring 26, the washer 27 is made of such diameter that it closely fits the bore 7 of the casing.

By reason of the presence of the heat-absorbing tube 25, a refill, that is ordinarily adapted for use in circuits carrying current up to five amperes, may be used for circuits carrying higher amounts of current, and the time interval at which the cutout operates to open the circuit may be varied by varying the dimensions of the heat-absorbing tube 25.

The cutout device is also effective for interrupting short-circuits and, under short-circuit conditions, the temperature of the end of the heating conductor attached to the disc 18 is initially raised to the fusing temperature of the solder because of the absence of heat-conducting metal in the immediate vicinity of the solder joint.

The open end of the casing 6 is closed by a threaded cap 29 having an opening 30 that is closed by a transparent mica disc 31. The disc serves as a stop for the disc member 17 and the device visibly indicates when the circuit has been interrupted. It will be seen from the foregoing that the construction is inexpensive to manufacture and comprises but few simple parts.

In Fig. 4, I have shown a modified construction similar to the construction illustrated in Fig. 1, with the exception that the heat-absorbing tube 25 is attached to the terminal member 9 by means of a threaded neck 32 on the latter member which is screwed into the socket 33 in the inner end of the tube 25. The heat-absorbing tube remains stationary and the contact disc 17 is moved to circuit-interrupting position by an insulating sleeve 34 having a radially-extending flange 35 which closely fits within the bore 7 of the casing 6.

A helical spring 26 serves to force the sleeve into engagement with the contact disc 17 and to move the disc 17 away from the soldered end of the heating conductor 19, when the solder connecting the disc and conductor is fused. The flange 35 protects the spring 26 from the arc gases incident to the interruption of the circuit. The insulating tube 34 also serves to confine the arc therein and to protect the terminals 14. As in the previously described device, refills may be repeatedly inserted.

Referring to Fig. 5, I have shown there-in a further modification of the device wherein the casing 6 is constructed substantially in the manner shown in my copending application previously referred to. In this construction, the refill comprises a contact disc 17 that is soldered to a heating conductor 19 which is retained in the casing in a manner

similar to that of the devices previously described. The contact disc 17 engages a heat-radiating disc 36 that is flexibly connected to the terminal sleeve 13 by a flexible metallic strip 37 and a terminal extension 38 that is attached to the sleeve. The flexible strip is connected to the disc 36 by means of a rivet 39.

A heat-absorbing tube 25 surrounds the heating conductor 19 and is connected, at its inner end, to a disc 41 which supports a helical spring 42. The spring engages an insulating washer 43 that is disposed between the spring and the inner end of an insulating barrier tube 44 which engages, at its upper end, the inner surface of the disc 36.

When the solder 45 joining the disc 17 and the heating conductor 19 becomes fused, the spring 42 forces the barrier tube 44 outwardly, carrying with it the disc 36 and the contact disc 17. The barrier tube 44 and the disc 36 prevent the rapid escape of arc gases out of the opening 46 through which the extension 38 projects, and the insulating washer 43 protects the spring 42 from arc gases.

As in the former device, the device may be repeatedly used by replacing refills after each circuit-interrupting operation.

While I have described and illustrated several embodiments of my invention, it will be apparent to those skilled in the art that various changes, modifications, substitutions, additions and omissions may be made in the apparatus illustrated without departing from the spirit and scope of my invention, as set forth in the appended claims.

I claim as my invention:

1. In a cut-out for electric circuits, the combination with a pair of relatively movable terminal members and a thermally-responsive heating conductor releasably connecting the terminal members and adapted to open the circuit when the conductor attains a predetermined temperature, of a heat-absorbing member surrounding the conductor and influencing the heating characteristics of the conductor.

2. In a cutout for electric circuits, the combination with a pair of terminal members and a one-piece composite thermally-responsive member having separable parts releasably engaging the terminal members and joined by a solder fusible at low temperature, of a heat-absorbing member adjacent both said parts and influencing the heating characteristics thereof.

3. In a cutout for electric circuits, the combination with a pair of terminal members and thermal-responsive element comprising a heating conductor connected to one of the terminal members by a fusible member, of a heat-absorbing member surrounding the heating conductor and movable over the end thereof when the conductor has become disconnected from the said terminal.

4. A cutout for electric circuits comprising

a pair of terminal members, a thermal-responsive element comprising a heating conductor for releasably engaging one of the said terminal members and connected to the other terminal, a heat-absorbing member surrounding the heating conductor and means for moving the heat-absorbing member over the disengaged end of the heating conductor when the latter is released from the first said terminal members.

5. A cutout for electric circuits comprising a terminal, a contact member for engaging the terminal, a heating conductor soldered to the contact member and adapted to be separated therefrom for interrupting the circuit when the heating conductor attains a predetermined temperature, and a heat-absorbing member surrounding the heating conductor and movable over the disengaged end thereof for moving the contact member out of engagement with the terminal member, when the heating member has become disengaged from the contact member.

6. A cutout for electric circuits, comprising a casing having a yielding terminal member and a fixed terminal member, a contact member for engaging the yielding terminal member, a heating conductor releasably connected to the contact member and adapted to be released therefrom when the conductor is heated to a predetermined temperature and detachably connected to the fixed contact member, and a heat-absorbing element surrounding the heating conductor and movable over the released end thereof for separating the contact member from the terminal member when the heating conductor is released from the contact member.

7. A cutout for electric circuits comprising a tubular casing having one end closed and provided with a fixed terminal, a yielding terminal adjacent the open end thereof, a contact disc for slidably and releasably engaging the terminal, a heating conductor detachably connected to the contact disc and responsive to current therein for releasing the contact member, means for detachably connecting the heating conductor to the fixed terminal, a movable heat-absorbing member adjacent the heating conductor and means for moving it for separating the said contact member from the heating conductor when the former is released.

8. A cutout for electric circuits comprising a tubular casing having one end closed and provided with a fixed terminal, a yielding terminal within the casing, a thermal-responsive refill having a contact member releasably engaging the yielding terminal and a heating conductor soldered thereto detachably engaging the fixed terminal, a spring member within the casing and an operating member operable by the spring for moving the contact member out of engagement with the yielding terminal having a portion closely fitting the

inner walls of the casing for protecting the spring from arc gases incident to separation of the contact member and heating conductor.

9. The combination, in a fuse cutout, of
5 insulating means for supporting a pair of terminals, a fuse element comprising a heat-conducting member soldered to a releasable member, means for releasably supporting the fuse element across the terminals, and heat-
10 absorbing means adjacent the fuse element for obtaining a time lag in the operation of the cutout.

10. In combination with a fuse cutout comprising an insulating casing and a pair of
15 terminals, of a composite renewable fuse element comprising a heat-conducting element soldered to a current-conducting member, means for releasably supporting the fuse element across the said pair of terminals, and

means adjacent to the fuse element for producing a time lag in the operation of the cutout.

11. In combination with a fuse cutout comprising an insulating casing and a pair of terminals, of a composite renewable fuse element comprising a heat-conducting element soldered to a current-conducting member, means for releasably supporting the fuse element across the said pair of terminals, and means adjacent to the fuse element for producing a time lag in the operation of the cutout, said time lag being in inverse proportion to the increase in current in the circuit.

In testimony wherof, I have hereunto subscribed my name this 9th day of January, 35
1923.

MAURITS J. SANDIN.
